UNITED STATES PATENT OFFICE

LAWRENCE R. LOVELAND, OF WASHINGTON, DISTRICT OF COLUMBIA

DESIGN FOR A COMBINED CIGAR LIGHTER AND PAPER WEIGHT

Application filed January 8, 1932. Serial No. 42,417. Term of patent 14 years.

To all whom it may concern:

Be it known that I, LAWRENCE R. LOVELAND, a citizen of the United States, residing in Washington, D. C., have invented a new, original, and ornamental Design for Combined Cigar Lighter and Paper Weight, of which the following is a specification, reference being had to the accompanying drawings, forming part thereof, wherein:

Figure 1 is a front elevational view of the combined cigar lighter and paper weight showing my new design; and,

Figure 2 a side elevational view thereof.

I claim:—

The ornamental design for a combined cigar lighter and paper weight as shown.

LAWRENCE R. LOVELAND.
